UNITED STATES PATENT OFFICE.

BENNO B. LEUSTIG, OF CLEVELAND, OHIO.

RAIL-SUPPORT.

1,273,508.

Specification of Letters Patent. Patented July 23, 1918.

Application filed April 23, 1918. Serial No. 230,232.

To all whom it may concern:

Be it known that I, BENNO B. LEUSTIG, a citizen of the United States, residing at Cleveland, in the county of Cuyahoga and State of Ohio, have invented a new and useful Rail-Support, of which the following is a specification.

This invention relates to improvements in rail-supports, and pertains more especially to a rail-support comprising a railway tie having a metal body which is adapted to extend below and transversely of the rails of a railway track and is provided with two insulating blocks seated on said body and adapted to be employed in supporting said rails.

One object of this invention is not only to provide said body with blocks for supporting said rails but to have said blocks adequately secured to said body and readily removable for repairs or renewal.

Another object is to render my improved rail-support simple and durable in construction and to facilitate the assemblage of the component parts thereof.

With these objects in view, and to attain any other object hereinafter appearing, this invention consists in certain features of construction, and combinations and relative arrangement of the parts, hereinafter described in this specification, pointed out in the claims and illustrated in the accompanying drawings.

In said drawings, Figure 1 is a top plan of a portion of a railway track comprising a rail-support embodying my invention. Fig. 2 is a side elevation of said rail-support. Fig. 3 is a horizontal section taken along the line 3—3, Fig. 2, looking downwardly. Fig. 4 is a vertical section taken along the line 4—4, Fig. 2, looking outwardly. Fig. 5 is a vertical section taken along the line 5—5, Fig. 2, looking in the direction indicated by the arrow.

My improved rail-support is shown as comprising a railway tie having a metal body A which is preferably T-shaped in cross-section and adapted to extend below and transversely of the rails of a railway track, and said body (see Figs. 2 and 4) has two seats 10 formed by the top and spaced longitudinally of the body and is provided between said seats with a substantially vertically upwardly projecting flange 12 arranged centrally between the side edges of

the top and extending longitudinally of the body.

Two blocks B, which are circular in plan and adapted to be employed in supporting the rails of a railway track, are seated the one on one of the seats 10 and the other on the other of said seats, and C, Fig. 1, indicates rails seated on said blocks and secured to the blocks in any approved manner, as, for instance, by suitably applied spikes 8. Each block B is preferably composed of material,—such, for instance, as wood,—which is a non-conductor of electricity, so as to render the block suitable for insulating the rail which may be seated thereon from the body A. Each block B is attached to the adjacent portion of the flange 12, and preferably a metal strap D, having one end portion thereof extending opposite one side of and secured to said portion of said flange, 75 extends from said side of said flange circumferentially of and embraces and frictionally engages said block and has its other end portion extending opposite the other side of and removably secured to said portion of said flange. Preferably one end portion of said strap is secured by rivets 13 to said flange, and the other end portion of said strap is secured to said flange by suitably applied bolts 14 and nuts 15 and, as shown more clearly in Fig. 3, is provided with holes d to accommodate the location of the rivets 13. The shanks of said bolts extend laterally and loosely through said flange and laterally and loosely through said end portions of said strap and have their heads 16 arranged at the outer side of one of said end portions of said strap, and the nuts 15 are threaded onto said shanks at the outer side of the other of said end portions 90 of said strap, and obviously manipulation of said nuts as required to loosen them relative to said strap results in loosening said strap relative to the block B embraced by the strap and renders said block free to be removed upwardly as required to replace the block by a new one.

The body A is provided between each seat 10 and the adjacent end of said body with a substantially vertically upwardly projecting flange 18 which is arranged centrally between the side edges of the top and extends longitudinally of said body, and said flange and the hereinbefore mentioned flange 12 are arranged in line endwise and at diamet- 110

rically opposite sides respectively of the adjacent block B which engages the space between adjacent ends of said flanges. Preferably each block B projects somewhat above the embracing strap D and above the adjacent flanges 12 and 18, so that a rail seated on said block will not make contact with said strap. By the construction hereinbefore described it will be observed that the body 5 A is provided with two outer upwardly projecting flanges 18 extending along opposite end portions respectively of said body and a central or intermediate flange 12 arranged between and spaced from said outer flanges, 10 and that between said intermediate flange and each outer flange is arranged a block B. I would here remark that each block B (see Figs. 2 and 3) is shown provided at its lower end and external circumferential surface, adjacent 15 the inner end of the adjacent outer flange 18 of the body A, with a recess 20 which extends to the lower extremity of said block. The strap D embracing said block extends circumferentially of the recessed 20 portion of the block and is provided opposite the recess 20 in the block with a slot 21 which registers with said recess and extends to the bottom edge of said strap, and the adjacent outer flange 18 of the body A has its 25 lower portion projecting, as at 22, through said slot and into said recess, and obviously the engagement of said portion of said flange with said slot and with said recess positively prevents displacement of said block transversely of said body and circumferentially 30 internally of said strap.

By the construction and relative arrangement of the parts hereinbefore described it will be observed that each block B constitutes 35 a readily renewable support for the rail to be seated on said block and has the recessed portion thereof straddling the portion 22 of the adjacent flange 18 and is consequently locked against displacement transversely of the body A from which said block 40 is supported.

What I claim is—

1. The combination, with the body of a railway tie, said body being adapted to extend below and transversely of the rails of a railway track and having two seats which are formed by the top and spaced longitudinally of the body and being provided between said seats with an upwardly projecting flange 45 extending longitudinally of the body, and two blocks adapted to be employed in supporting said rails and arranged the one over one of said seats and the other over the other of said seats, of a strap for each block for attaching said block to said flange, said strap embracing said block and being secured to said flange.

2. In a rail-support, a body adapted to extend below and transversely of the rails of a 50 railway track and having two seats which

are formed by the top and spaced longitudinally of the body and being provided between said seats with an upwardly projecting flange extending longitudinally of the body, two blocks adapted to be employed in supporting said rails and arranged the one over one of said seats and the other over the other seat, and a metal strap embracing said block and having one end portion thereof extending opposite one side of and secured to said flange and having its other end portion extending opposite the other side of and removably secured to said flange. 70

3. In a rail-support, a metal body adapted to extend below and transversely of the rails of a railway track and having two seats which are formed by the top and spaced longitudinally of the body and being provided between said seats with an upwardly projecting flange extending longitudinally of the body, two insulating blocks adapted to be employed in supporting said rails and seated on said seats, and a metal strap for each block for attaching said block to said flange, said strap embracing said block and having its end portions secured to said flange, and said block projecting above said strap. 80

4. In a rail-support, a body adapted to extend below and transversely of a rail and having two upwardly projecting spaced flanges, and a block occupying the space between said flanges and supported on said body and constituting a support for the aforesaid rail, said block being attached to one of said flanges, and the other of said flanges having a portion extending into said block. 90

5. In a rail-support, a body adapted to extend below and transversely of a rail and having two upwardly projecting flanges which extend and are spaced longitudinally of the body, a block occupying the space between said flanges and supported on said body and being circular in plan and constituting a support for the aforesaid rail, a metal strap extending circumferentially of said block and having its end portions secured to one of said flanges, and means at the adjacent end of the other of said flanges for preventing displacement of said block transversely of the aforesaid body. 105

6. In a rail-support, a body adapted to extend below and transversely of a rail and having two upwardly projecting spaced flanges, a block occupying the space between said flanges and supported on said body, and a metal strap embracing said block and attached to one of said flanges, said block straddling a portion of the other of said flanges. 110

7. In a rail-support, a body adapted to extend below and transversely of a rail and having two upwardly projecting spaced flanges, a block seated on said body between said flanges and constituting a support for 120

said rail, and a strap embracing said block and provided with a slot and attached to one of said flanges, the other of said flanges having a portion thereof extending through 5 said slot and into said block.

8. In a rail-support, a body adapted to extend below and transversely of a rail and having two upwardly projecting spaced flanges, a block occupying the space between 10 said flanges and supported on said body, said block being circular in plan and constituting a support for the aforesaid rail and being provided, at its external circumferential surface, with a recess, and a metal strap 15 extending circumferentially of the recessed portion of said block and provided with a slot arranged to register with said recess, one of said flanges having a portion thereof extending through said slot and into said 20 recess, and the aforesaid strap being attached to the other of said flanges.

9. In a rail-support, a body adapted to extend below and transversely of a rail and having two upwardly projecting spaced 25 flanges, a block supported on said body between said flanges and constituting a support for said rail, and a strap embracing said block and attached to one of said flanges, the other of said flanges having the 30 lower portion thereof extending, at the lower end of said block, through the adjacent portion of said strap and into said block.

10. In a rail-support, a body adapted to 35 extend below and transversely of a rail and having two upwardly projecting spaced

flanges, a block occupying the space between said flanges and supported on said body, said block being circular in plan and constituting a support for the aforesaid rail and 40 being provided, at the lower end of its external circumferential surface, with a recess which extends to the lower extremity of the block, and a strap extending circumferentially of the recessed portion of said block 45 and provided with a slot which registers with said recess, one of the aforesaid flanges having the lower portion thereof extending through said slot and into said recess, and said strap being attached to the other of 50 said flanges.

11. In a rail-support, a body adapted to extend below and transversely of the rails of a railway track and provided with three upwardly projecting flanges extending and 55 spaced longitudinally of the body and arranged the one intermediately of the others, and blocks supported on said body and occupying the spaces between the intermediate flange and the outer flanges said blocks 60 constituting supports for the aforesaid rails, and each block being connected to the intermediate flange and to the adjacent outer flange.

In testimony whereof, I sign the foregoing specification, in the presence of two witnesses.

BENNO B. LEUSTIG.
